CLAIM

The ornamental design for a clip with an aperture, as shown and described.

DESCRIPTION

FIG. 1 is a perspective view of a clip with an aperture; FIG. 2 is a front view of the clip shown in FIG. 1; FIG. 3 is a rear view of the clip shown in FIG. 1; FIG. 4 is a side view of the clip shown in FIG. 1; FIG. 5 is another side view of the clip shown in FIG. 1; FIG. 6 is a top view of the clip shown in FIG. 1; FIG. 7 is a bottom view of the clip shown in FIG. 1; and, FIG. 8 is a perspective view of the clip shown in FIG. 1 with the clip shown in place on a portable dispenser.

The subject matter depicted in broken lines merely shows optional features of the clip and provides a context for the use of the clip without forming any part of the claimed design.
